TOY SUBMARINE

Frederick Sabini, Salem, N. J.

Application August 23, 1946, Serial No. 692,444

5 Claims. (Cl. 46—94)

1

This invention relates to improvements in toys; and the invention has reference, more particularly, to improvements applicable to toy submarines of the types disclosed in my copending applications for Letters Patent Ser. No. 506,305 filed October 15, 1943, and Ser. No. 674,165, filed June 4, 1946.

The invention has for an object to provide, in combination with a toy submarine construction of the self-submerging type, means to automatically release the toy upon completion of a full submerging dive, so that the same will rise through the water in which it has submerged and thus return to the water surface.

Another object of the invention is to provide, in connection with the bottom of the hull of the submarine toy, a releaseable ballasting weight having means to contact the bottom surface which underlies the water in which the toy is operated whereby to move said weight to released position.

Another object of the invention is to provide, in connection with the bottom of the hull of the submarine toy, a releaseable ballasting weight and means for supporting the same for carriage by said hull; said ballasting weight being selectively shiftable to different supported positions, whereby to control the character of the submerging movement of the toy, so that the latter may be optionally caused to submerge in an oblique nose dive or to submerge while maintaining a substantially horizontal or level keel position.

Other objects of this invention, not at this time more particularly enumerated, will be understood from the following detailed description of the same.

An illustrative embodiment of this invention is shown in the accompanying drawings, in which:

Fig. 1 is a side elevational view of a self-submerging toy submarine equipped with the novel releasable ballasting weight according to this invention, showing said weight as operatively supported in connection with the hull bottom, while the toy submarine is afloat upon the water; Fig. 2 is a vertical cross-sectional view, taken on line 2—2 in Fig. 1; Fig. 3 is a view similar to that of Fig. 2, but showing the ballasting weight in released relation to the submerged toy submarine (shown by broken lines), the risen toy submarine, as returned to the surface of the water, being shown by full lines; and Fig. 4 is a fragmentary horizontal sectional view, taken through the horizontal plane of the line 4—4 in Fig. 2.

2

Similar characters of reference are employed in the above described views, to indicate corresponding parts.

Referring to the drawings, the features of the 5 instant invention are shown for the purpose of illustration, as applied to the hull of a toy submarine of the self-propelled and self-submerging type, such as disclosed in my co-pending application Ser. No. 674,165, filed June 4, 1946, but it 10 will be obvious that said features are equally applicable to the simple self-submerging type of toy submarine disclosed in my co-pending application Ser. No. 506,305, filed October 15, 1943, now Patent Number 2,405,715, as well as 15 to other forms of submersible toys.

As illustratively shown, the toy submarine comprises a hollow body or hull formed by a bottom portion 10, side portions 11 and top or deck portion 12; said body or hull being suitably shaped to simulate the appearance of a submarine. Said body or hull may be made of any suitable material, such e. g. as sheet metal, plastic material, wood, etc. Joined to and rising from the top or deck portion 12 of the hull is a 20 hollow body extension 13, which may be suitably shaped to simulate the conning tower of a submarine. Said hollow body extension 13 is open at its bottom so as to communicate with the interior of the hull, and its interior provides 25 an air trapping chamber 14 for purposes hereinafter disclosed. Extending perpendicularly through the interior of the air trapping chamber 14 and thence through the top of the body extension 13, so as to project exteriorly from 30 the latter in upstanding relation thereto is a tubular periscope simulating member 15, which is adapted to provide an endwise open air vent 35 passage 16, the lower end of which terminates at the approximate bottom level of said air trapping chamber 14.

Indenting the bottom 10 of the hull body is a longitudinally extending, downwardly and outwardly open ballast weight housing chamber 20. Receivable in said housing chamber 20 is an 40 elongated ballasting weight 21, which is of less length than the length of said housing chamber, so as to be longitudinally shiftable therein to selectively position the same relative to the hull body for purposes hereinafter referred to. Said ballasting weight 21 is preferably of substantially cylindrical shape, but is cut away at 45 opposite sides to provide flat lateral faces 22 and 23, thus reducing the lateral diameter of the weight as compared with its diameter at right 50 angles thereto, whereby the lateral diameter con-

stitutes the minor diameter and the diameter at right angles thereto the major diameter thereof.

Affixed to the hull body bottom 10, so as to border one side of said weight housing chamber 20 and to depend from said bottom 10, is a supporting bracket comprising an attachment flange 24, which is suitably secured to the hull body bottom 10, an inwardly offset supporting flange 25 which underlies one side of the housing chamber 20, said flange 25 terminating in an outwardly projecting horizontal foot-piece 26. Similarly, affixed to the hull body bottom 10, so as to border the opposite side of said weight housing chamber 20 and to depend from said bottom 10, is a second supporting bracket which is opposed to said first mentioned supporting bracket. Said second supporting bracket also comprises an attachment flange 27 which is suitably secured to the hull body bottom 10, an inwardly offset supporting flange 28 which underlies said opposite side of the housing chamber 20, said supporting flange 28 likewise terminating in an outwardly projecting horizontal foot-piece 29. Said supporting flanges 25 and 28 are spaced apart at their lower ends for a distance slightly in excess of the minor diameter of the ballasting weight, thus providing an escape or release passage 30 through which, when the major diameter of the weight is aligned therewith, said weight may pass out of the housing chamber 20 to permit mutual separation of the hull body and weight. Extending from said ballasting weight, in angular relation to the major diameter thereof, is a lever arm 31 which is operative, under proper conditions, to rotate the weight about its longitudinal axis, so as to bring its major diameter into alignment with the weight escape or release passage 30, with the lateral faces 22 and 23 of the weight parallel to the sides of said passage, whereby the weight is removed from the support of said supporting flanges 25 and 28.

Said second supporting bracket is indented by lateral or transverse slots comprising a forward slot 32 and a rearward slot 33 which extend through the foot-piece 29 and thence upwardly through the supporting flange 28. Said slots are suitably spaced apart in the direction of the longitudinal extent of the housing chamber 20, subject to selective extension therethrough of the lever arm 31, according to a selected forwardly disposed or rearwardly disposed position in which the ballasting weight is desired to be set.

To assemble the ballasting weight 21 in operative supported connection with the hull body, the weight is turned about its longitudinal axis so as to align its perpendicular major diameter with the passage 30 of the supporting bracket means, whereupon the weight may be passed upwardly through the latter and into the housing chamber 20, while at the same time passing the lever arm 31 through a selected slot 32 or 33 of said supporting bracket means. After being thus entered in the housing chamber 20, the lever arm 31 is swung downward to turn the ballasting weight about its longitudinal axis, whereby to shift the major diameter so that it crosses the passage 30, whereby the weight is caused to rest upon and bridge across the opposed supporting flanges 25 and 28 of the supporting bracket means, and is thereby retained in supported connection with the hull body so as to be carried thereby. When the ballasting weight is thus turned to its supported position, the lever arm 31 will be projected therefrom so as to incline downwardly and outwardly therefrom, with its free

end projected below the plane of the foot-pieces 26 and 29 of the supporting bracket means (see Figs. 1 and 2).

Connected between the ballasting weight 21 and some attached part of the hull body is a flexible line or cord 34 for tethering the former to the latter.

In the use and operation of the toy submarine, the hull being empty, and the ballasting weight being supportedly assembled therewith, the same is set afloat upon the surface of the water. Water will thereupon be admitted to and so as to eventually fill the interior 17 of the hull body, optionally for and in the manners fully described in my aforementioned prior patent application disclosures, the displaced air being vented through the periscope air vent passage 16, or through other suitable vent means. The entering water eventually rises within the hull body interior 17 to the bottom of the air trapping chamber 14 and the lower end of the periscope air vent passage 16, whereby to seal off the chamber 14 and thus trap the air therein so as to provide a buoyant float adapted, when conditions permit, to buoy up the submerged submarine so as to cause the same to rise through the water to the surface thereof. The heft of the ballasting weight 21 is such, however, that its gravity will overbalance and counteract the buoyant effect of the air trapped within the chamber 14, so long as said ballasting weight remains in supported connection with the hull body. As a consequence of this, the water admitted into the interior 17 of the hull body will cause the toy submarine to dive or submerge, and its submerging descent will continue until the same reaches and touches bottom.

When the toy submarine, upon the conclusion of its dive, reaches bottom, the free end of the lever arm 31 will strike bottom, and as borne against the same by the settling hull body, will be upswung. Such upswinging movement of the lever arm 31 will rotate the ballasting weight 21 about its longitudinal axis, whereby to bring its major diameter into vertical position, thus removing the ballasting weight from bridging and supported relation to the supporting flanges 25 and 28, so that the minor diameter of said weight takes a horizontal position in said passage 30 (see Fig. 3). Under these circumstances the ballasting weight 21 no longer bears down the hull so as to counteract the buoyant effect of the air trapped within the chamber 14, and consequently the latter becomes operative to buoy up and cause the toy submarine to rise through the water and to ascend to the surface, as indicated by full line representation thereof in Fig. 3. As the hull body rises, the ballasting weight passes through the passage 30 of the supporting bracket means so as to be left behind on the bottom. As this occurs, the line or cord 34 pays out from the hull body, whereby to cause the ballasting weight 21 to anchor the risen toy submarine against escape. The line or cord 34 also serves as a means to draw up and recover the ballasting weight 21 from the bottom, when it is desired to obtain the same for reassembly with the hull body, for repeated use and operation of the toy.

As above indicated, the ballasting weight 21 may be selectively operatively assembled with the hull body in either a forwardly or rearwardly shifted position. When disposed in a forwardly shifted position, as shown in Fig. 1, the weight is set toward the bow, so that the bow will tend to somewhat overbalance the stern of the hull body as the water enters the interior 17 of the

latter, and consequently the toy submarine will tend to submerge in a manner simulating a bow or nose foremost dive. The ballasting weight is retained in such forwardly set position by engagement of its lever arm 31 in the forward slot 32 of the bracket supporting means. When, on the other hand, the weight 21 is disposed in a rearwardly shifted position, it is set further toward the stern so as to substantially balance the center of gravity of the toy submarine at a point midway between the bow and stern thereof, and consequently the toy submarine will tend to submerge in a horizontal or level keel position as the water enters the interior 17 thereof. The ballasting weight is retained in such rearwardly set position by engagement of its lever arm 31 in the rearward slot 33 of the bracket supporting means. It may be here pointed out, that the adjustably shiftable ballasting weight may be utilized merely for its center of gravity regulating effect, with or without the self-releasing effect and attendant hull body raising result.

The flat or horizontal foot-pieces 26 and 29 of the supporting bracket means are additionally useful for service as a stand for support of the toy submarine when removed from the water, and also as skidding supports which will hold the toy upright when used as a pull toy; and dragged over a floor or other similar surface.

I am aware that various changes can be made in the above described novel features of my toy submarine or the like without departing from the scope of this invention as defined in the hereinafter claims. It is therefore intended that all matter contained in the above description or shown in the accompanying drawings shall be interpreted as illustrative and not in a limiting sense.

I claim:

1. In a toy submarine of the kind described, a hollow hull body to which water is admissible when it is set afloat, air venting means communicating with the interior of said hull body, said hull body having at its top portion means to provide an air chamber adapted to buoy said hull body against the weight of water entered therein, a ballasting weight, said hull body having a downwardly open weight housing chamber at the bottom thereof, said weight having a major diameter and a minor diameter, weight supporting bracket means bordering the sides of said housing chamber, said supporting bracket means being spaced apart to provide a weight passage of a width slightly larger than the minor diameter of said weight, said weight being disposed with its major diameter across said supporting bracket means whereby to connect the weight with the

hull body, said weight being turnable about its longitudinal axis whereby to place its minor diameter in a horizontal position within said weight passage so as to permit release of the weight from said hull body, and a lever arm extending from said weight operative, after submergence of the toy submarine, upon contact with the bottom to turn said weight to released position.

2. In a toy submarine as defined in claim 1, a flexible line to provide a tethering connection between said ballasting weight and said hull body.

3. In a toy submarine of the kind described as defined in claim 1 wherein the weight housing chamber is of greater length than the weight so that the latter can be longitudinally adjusted in the former, whereby to shift the center of gravity of the hull body as ballasted by said weight.

4. In a toy submarine of the kind described, a hollow hull body to which water is admissible when it is set afloat, air venting means communicating with the interior of said hull body, means to buoy said hull body against the weight of water entered therein, a ballasting weight, said hull body having a downwardly open weight

20 housing chamber at the bottom thereof, said weight having a major diameter and a minor diameter, weight supporting means bordering the sides of said housing chamber and laterally spaced to provide a weight passage of a width slightly larger than the minor diameter of said

30 weight, said weight being disposed with its major diameter across said supporting means whereby to connect the weight with the hull body, said weight being turnable about its longitudinal axis whereby to place its minor diameter in a horizontal position within said weight passage so as to permit release of the weight from the hull body, and means operative, after submergence of the hull body, to turn said weight to released position.

5. In a toy submarine of the kind described as defined in claim 9, wherein the weight housing chamber is of greater length than the weight so that the latter can be longitudinally adjusted in the former, whereby to shift the center of gravity of the hull body as ballasted by said weight.
